UNITED STATES PATENT OFFICE.

JOHN F. FITZGERALD, OF WORCESTER, MASSACHUSETTS, ASSIGNOR OF ONE-HALF TO FRANK STORMS, OF SAME PLACE.

WRENCH.

SPECIFICATION forming part of Letters Patent No. 531,628, dated January 1, 1895.

Application filed April 22, 1892. Serial No. 430,175. (No model.)

To all whom it may concern:

Be it known that I, JOHN F. FITZGERALD, a citizen of the United States, residing at Worcester, in the county of Worcester and 5 State of Massachusetts, have invented a new and useful Improvement in Wrenches, of which the following is a specification, accompanied by drawings, forming a part of the same, and in which—

10 Figure 1 is a side view of a wrench embodying my invention. Fig. 2 is a central vertical sectional view of the handle. Fig. 3 is a transverse section on line 3, 3, Fig. 1, and Fig. 4 is an elevation of the fixed and sliding 15 jaws showing the side opposite that shown in Fig. 1.

Similar letters refer to similar parts in the several figures.

My invention has for its object to provide 20 means, whereby the sliding jaw may be engaged, or disengaged at will from the actuating screw; and, also to provide means by which the bar is relieved of the strain brought upon the ferrule when the wrench is in use.

25 Referring to the drawings, A denotes the bar provided with the fixed jaw A'.

B is the sliding jaw, provided with a recess, or chamber, to receive the actuating screw C. Inserted within the sliding jaw and pivoted 30 at E' is a half-nut E arranged to engage the screw C and be held in contact therewith by a spring F attached to the sliding jaw with its free end bearing against the half-nut E. The half-nut E fills the recess made in the 35 sliding jaw so that any end thrust will be received by the walls G, G'. The free end of the nut E is preferably made with a projecting point H forming a surface I upon the end adapted to receive the thumb and allow the 40 nut to be swung upon the pivot E', against the tension of the spring F, far enough to disengage the screw C and allow the sliding jaw to be moved up and down the bar A, by the pressure of the nut E against the walls 45 G, G' of the sliding jaw. As soon as the nut E is released, the action of the spring F serves to carry the nut into engagement with the screw C, allowing the adjustment of the sliding jaw by the action of the screw.

50 I am aware that half-nuts, pivoted upon

the sliding jaw and arranged to engage the actuating screw, are not new; but by hanging the half-nut upon a pivot and arranged to swing in a horizontal plane between the retaining walls G, G' I relieve the pivotal connection of all strain and arrange the nut in a position for the convenient manipulation of the sliding jaw. 55

J denotes the ferrule, inclosing the bar A, which is screw-threaded at A² to receive the 60 screw threaded end of a metallic sleeve K, whose upper end rests against a shoulder J' on the ferrule J. The metallic sleeve K incloses the bar A and extends downward with its lower end bearing against the upper surfaces of the tip nut L. Any downward strain upon the ferrule J is therefore received by the tip nut L and by screwing the tip nut against the lower end of the sleeve K, which is held from upward movement along the bar by the 70 screw threaded section A², the tip nut acts conjointly with the sleeve K to produce a strain upon the screw threaded sections of the bar A, the tip nut L becoming a check nut. 65

The wood handle N is held between the tip 75 nut L and the ferrule J in the usual manner, but is relieved from all strain as the distance between the end of the ferrule and the tip nut can never be shortened by the downward movement of the ferrule. 80

I am aware that the bar of a wrench has been made screw threaded beneath the ferrule to receive a collar, which would prevent the longitudinal movement of the ferrule and I do not claim such. 85

What I claim as my invention, and desire to secure by Letters Patent, is—

1. The combination with the actuating screw of a wrench and a sliding jaw recessed to receive said actuating screw and provided 90 with the opposing walls G, G' in parallel planes at right angles with the axis of said actuating screw, of a half nut pivoted to said sliding jaw at E' and held between the walls G, G', and a spring F attached to said sliding jaw 95 and applied to hold said pivoted half nut in contact with said screw, substantially as described.

2. In combination with the screw C and sliding jaw B recessed to receive said screw 100

and provided with the opposing walls G, G' at right angles with the axis of said screw, a half nut E held between said walls and pivoted at E' upon one side of said sliding jaw 5 and in front of the rear side of the screw C, a spring F attached to the sliding jaw and applied to hold the half nut in contact with said screw, and a projecting point H upon the free end of said half nut, substantially as described.

3. The combination with the bar A, ferrule J and tip nut L, said bar being provided with

a screw threaded section A², of a sleeve K provided with an internal screw thread and screwed upon the section A² with its upper 15 end abutting against said ferrule and its lower end bearing upon said tip nut, substantially as described.

Dated the 14th day of April, 1892.

JOHN F. FITZGERALD.
